INVENTOR;
BY WALLACE C. YEOMANS.
Honorable Barnes.
ATTORNEY

UNITED STATES PATENT OFFICE.

WALLACE C. YEOMANS, OF PORTLAND, OREGON, ASSIGNOR TO YEOMANS CONCRETE TIE, INC., A CORPORATION OF OREGON.

RAILWAY TIE.

Application filed November 15, 1927. Serial No. 233,353.

This invention relates to railway ties and particularly to composite ties of cement and metal.

The object of the invention is to provide 5 railway ties of simple and practical construction each comprising a pair of spaced blocks of plastic composition and connected together by pliable metal rods arranged to maintain the blocks in suitable relative positions.

A further object of the invention is the provision of a railway tie formed of separate blocks under each of the rails, respectively, suitably formed to receive metal 15 retaining rods to maintain the blocks in aligned positions and the rails at their proper gauge width.

A still further object of the invention is the provision of spaced concrete blocks for 20 supporting the rails and metal rods for tying said blocks in transversely disposed pairs, said blocks being grooved on their lateral surfaces to receive said rods externally at selective elevations.

25 A still further object of the invention is the provision of concrete railway ties provided with novel means for retaining the rails in detachably secured position thereon.

Other objects and advantages of my invention, and objects relating to details of 30 construction and arrangement of parts, will be readily apparent in the course of the detailed description to follow.

The accompanying drawings illustrate by 35 way of example a preferred form of my invention, in which:

Figure 1 is a perspective view of a railway tie of my invention in assembled condition, a portion of which is broken away 40 to disclose interior parts.

Fig. 2 is a fragmentary plan view of my invention.

Fig. 3 is a view in side elevation of the structure shown in Fig. 2.

45 Fig. 4 is a view in end elevation of Fig. 3.

Fig. 5 is a top plan view of a concrete block element of my improved railway tie with a portion of the upper surface removed.

50 Fig. 6 is a view in elevation of a metal end plate which may be employed interchangeably with the form shown in the preceding views.

Referring to said views, the reference 55 numeral 1 indicates a block formed of concrete or other suitable plastic material which

is substantially rectangular in plan and in end elevation. One of said blocks is designed to be placed under each of a pair of rails 2, respectively, the major axes of the blocks being in alignment and disposed 60 transversely to the line of the rails. The bottom surfaces of said blocks are desirably of greater depth in their middle portions than at their two extremities, said surfaces being of curved configuration, as indicated 65 in Fig. 1, or of angular configuration, as shown in Figs. 3 and 4, to facilitate tamping of the road bed thereunder. The upper surfaces of the blocks are formed with a centrally disposed transverse channel 5 in its 70 central portion to receive the rails 2, said channel being of greater depth than the edges of the rail flanges 6.

75 Retaining spikes 7 of malleable metal are imbedded vertically in the block upon each side of said channel, their inner surfaces being substantially flush with the respective lateral edges of the channel. Said spikes are formed with a laterally extending anchor portion 8 at the lower end, whereby 80 they are permanently retained in the concrete, and before assembly the upper projecting portions of the spikes extend vertically therefrom. Desirably a pair of said spikes are positioned upon each side of the 85 rail retaining channel in oppositely spaced relation, and upon the mounting of the rail upon the block said projecting ends of the spikes are bent over upon the rail flanges to fixedly secure the rail to the block.

Adjacent each lateral edge of the block and immediately below the surface of the channels 5 a bar 10 of corrugated metal is imbedded in the block material to reinforce 95 the edges of the channel and safeguard the same from fracture. Each of the blocks is formed with an aperture 11 extending longitudinally thereof in vertical line with its major axis. A metal rod 12 is passed through said aperture and extends through 100 a similar aperture in the companion opposing block. Said rods project from the outer end of said apertures where they are screw threaded to receive nuts 13 to bear upon a washer 15, as shown in Fig. 1, contacting 105 with the respective block-end or, as shown in Figs. 2 to 4, inclusive, upon a metal plate 16 apertured to accommodate said rod.

The blocks are formed on their lateral surfaces 17 with a plurality of grooves 18 of 110

semi-circular cross section extending horizontally and parallel. Metal rods 20 are received in said grooves further connecting each pair of blocks together through their 5 ends being extended through apertures of the metal plates 16 and fixedly secured thereto by nuts 21 engaged on the threaded ends of the rods engaging said plates with the desired amount of tension. The end apertures 10 of said plates being in register with the grooves 18 maintain the rods in close engagement in the respective grooves, and they may be further maintained in such engagement by a tie plate 22 provided with apertures through which the rods may be threaded and positioned in the space intermediate the inner ends of the blocks.

As further security for the rail against lateral displacement, as upon the outer side 20 of curves in the track, rail braces 23 may be secured to the outer block of the curve to take up the lateral thrust. Said rail braces may be formed with a body 25 engaging the outer side of the rail and a flange 26 provided with a pair of apertures registering with a pair of spaced recesses 27 extending vertically from the upper surface of the block through which expansion bolts 28 may be inserted through the flange of the 25 rail brace to rigidly secure the same to the block.

In practice the rail blocks are positioned in opposing relation and adjusted to the proper rail gauge by means of the tie rods 35 12. The rails 2 may then be seated in the channels 5 and rigidly secured therein by bending the spikes 7 over upon their opposing flanges. For light rails the tie rods 12 may be sufficient to retain the blocks in 40 position. Where heavier traffic is borne, or upon curves, the tie rods 20 are added to more efficiently maintain the tie blocks in their relative positions. The rods 20 may be disposed in the upper pair of grooves 18 45 which will be substantially in alignment with the tie rods 12 and slightly above or following the surface of the road bed. For heavier traffic the lower grooves may be employed in which the rods 20 are disposed, in which 50 arrangement the rods 20 and the rods 12 will lie in the apices of a triangle, thus giving more rigidity as the lower rods will be imbedded in the road bed. For extremely heavy traffic two or more pair of rods 20 55 may be employed. To this end I have provided a metal plate 30 (see Fig. 6) to engage the outer end of the blocks and which is apertured, as at 31, to receive a plurality of rods 20 on each side.

60 The advantages of my invention resides in its adaptability to all conditions of railroad building in that it may be utilized for

light track at a minimum of tie rod material or with the same form of block additional metal may be added to meet the requirements of traffic as the same is demanded. The individual blocks are of simple construction and economical of manufacture, are readily transported and handled, and the expense of building and maintenance 65 may be kept at a minimum. 70

From the foregoing description, taken in connection with the accompanying drawing, the advantages of the construction and application of my invention will be readily 75 apparent; but, while I have described the principle of operation of the invention, together with the devices which I now consider the best embodiment thereof, it will be understood that the structures shown are 80 merely illustrative and that such changes may be made therein as will lie within the scope of the following claims.

Having described my invention, what I claim, is:

1. A railway tie comprising a pair of rail-supporting blocks each formed with a transverse rail-receiving channel, means to secure a rail in said channel, said blocks being formed with a longitudinally disposed aperture and a plurality of horizontally arranged grooves in its lateral faces parallel with said aperture, a tie rod extending through said aperture and provided with nuts screwed on its projecting ends to secure 95 said blocks in adjusted positions, a pair of tie rods disposed in selected of said grooves having screw threaded ends, a plate engaging the end of each block apertured in register with said grooves through which 100 said pair of rods extend upon opposite sides of the block, and nuts screwed upon the ends of said pair of rods to bear upon said plate.

2. A railway tie, comprising a pair of rail-supporting blocks each formed with a plurality of horizontally disposed grooves in each of its lateral sides, a pair of tie rods extending in either of said grooves upon opposite sides connecting said blocks together, an apertured plate engaging the outer end of each of said block through which the tie rods extend to maintain them in close engagement with said grooves, and nuts screwed upon the outer ends of said rods engageable with said plates.

3. A railway tie, comprising a pair of rail-supporting blocks, a tie rod extending through apertures in said blocks, a pair of tie rods secured upon opposite side walls of the blocks, and an apertured plate engaging the entire face of each block through which said pair of tie rods are maintained in operative engagement with the blocks.

WALLACE C. YEOMANS.
